ROTARY MOTION CONVERTED INTO
RECIPROCATING MOTION

Fred De Cesaris, Johnston, R. I.

Application May 16, 1950, Serial No. 162,348

10 Claims. (Cl. 74—40)

1
This invention relates to a mechanism for converting rotary motion into reciprocating motion. One of the primary objects of the present invention is to provide an inexpensive, foolproof, compact, sturdy mechanism which can be adapted into a wide variety of housings or containers.

Another object of the invention is to provide a mechanism which can be manufactured in mass production and adapted to various housing units with a minimum of change in any one mass produced part.

Another object of the invention is to provide a mechanism which can be easily and readily adapted to containers for dispensing cigarettes, straws, tooth picks, matches and the like.

Still another object of the invention is to provide a mechanism which can easily and readily be adapted to open and close an electric circuit.

Other objects of this invention will be pointed out in part and become apparent in part in the following specification and claims.

Like reference numerals refer to like parts. In the accompanying drawings.

Figure 1 is a perspective view showing one of the many forms the housing containing the unique mechanism may take.

Figure 2 is a side elevational view of the mechanism showing the reciprocating levers in raised position.

Figure 3 is a side elevational view of the mechanism showing the reciprocating levers in lower position.

Figure 4 is a sectional view taken along line 4—4 of Figure 2.

Figure 5 is a rear elevational view of the cam as seen in the position shown along line 5—5 of Figure 4.

Figure 6 is a front elevational view of the unique mechanism showing the parts in the same position as viewed in Figure 2 with the exception that the mechanism is shown set within a container and the disk shaft is removed.

Figure 7 is a front elevational view of the unique mechanism showing the parts in the position they assume when due to inadvertance, accident or when a deliberate attempt is made to upset the mechanism by forcing the reciprocating lever down against the action of the control cam.

Figure 8 is a front elevational view showing the unique mechanism in the position the component parts are in if a delicate product or human finger is wedged between the cover and body of a container.

2
Figure 9 is a sectional view taken along line 9—9 of Figure 3 showing the stop pin for the tongue and lever with the tongue not quite resting on the pin.

5 **5** Figure 10 is a view similar to Figure 9 showing a modified adaption of the unique mechanism to an electrical circuit.

Referring to Figure 1, wherein is shown the design of a binnacle for use as a cigarette, match 10 or tooth pick holder. This figure represents one of many forms the housing, encompassing the mechanism of this invention, may assume.

Referring to Figures 2, 3, 6, 7 and 8 the mechanism consists of a U-shaped frame 11 provided 15 with a base 12, a short arm 13 and a long arm 14. Pivotedly mounted upon a shaft 16 housed in arms 13 and 14 of frame 11 is a bail 17 provided with a tongue 18 midway of its end pieces and a pin 19 fixed in the arm of the bail 17 20 nearest the long arm 14 of the U-shaped frame 11 and extending through a slot 21 in said arm 14.

A U-shaped bracket 22 having a base 23 and side arms 24 and 25 is fixed to base 12 of 25 U-shaped frame 11 by means of a pin 26 (see Figure 9) which rivets U-shaped bracket 22 and U-shaped frame 11 together. A lever 27 is pivotally mounted in arms 24 and 25 of U-shaped bracket 22 by means of ears 28 and 29 which 30 form an integral part of said lever 27.

A shaft 30 is secured to base 12 by means of a threaded end 31 on said shaft 30 and a nut 32. A slidible disk 33 provided with a sleeve 34 is freely mounted on shaft 30. The combined 35 weight of disk 33 and sleeve 34 cause the underside of the disk 33 to rest on lever 27. Shaft 30 is provided with a threaded portion 36 on its upper end. A bushing 37 is threaded to portion 36. The upper surface of a bushing 38, 40 which holds disk 33 and sleeve 34 together cooperates with the underside of bushing 37 to prevent disk 33 and sleeve 34 from being drawn off shaft 30 after nut 32 is screwed in position.

Long arm 14 of U-shaped frame 11 has a stud 45 40 riveted to its upper end (see Figure 4). A pin 41 used as an anchoring means for a spring 42 is riveted to long arm 14 at about midway of its length. Shaft 16 extends beyond the outside surface of long arm 14 as shown in 45 Figures 2 and 6 for a reason presently described.

Rotatably mounted on stud 40 (see Figures 4 and 5) is a disk 45 provided with an eccentric surface 46 on one face and a split hub 47 on its opposite face (Figures 2 and 3). A wheel 50, 55 which may take any fanciful shape and which is

shown as a ship's steering wheel in Figure 1 and a plain disk in Figures 2, 3 and 4, is provided with a split hub area 52 on its opposite face. Said split hub 52 co-acting with split hub 47 forms a clutch 48 when spring 53 is held in recess 5 hub area 51 by means of a nut 54 threaded to the end of stud 40.

A dog leg shaped lever 55 is provided with a concentric cam following area 56 (Figure 5) which co-operates with eccentric surface 46 to form a reciprocating link. The lower end of lever 55 is provided with a cam following surface 57, a pin carrying area 58 and an auxiliary cam area 59. Spring 42 is secured to lever 55 by means of a rivet 61.

Referring to Figure 6, a container 80 is secured to U-shaped bracket base 12 by means of spot welding. The conventional shaft 30 is done away with in this figure. Disk 33 is free to be raised by lever 27. As illustrated, disk 33 will not stay in a horizontal plane. However, when two or more disks or guide means are provided in container 80, the disk 33 will remain substantially horizontal in its up and down movement.

Referring to Figure 8, a container 80 is secured to U-shaped bracket base 12 in any conventional way as by spot welding. The relief aperture 81 in container base 80 allows for access to screw 32 fastened to shaft 30 at 31. The mechanism and container as shown in this figure may be placed in another container having a fanciful outward design, such as shown in Figure 1.

Figure 10 illustrates a microswitch 75 secured to post 30 by means of a conventional bracket 76. An electric light bulb 77 set in a conventional socket 78 is mounted on top of post 30. Current is supplied from any convenient source to terminals A and B. Tongue 18 functioning as before strikes microswitch button 79. Button 79 closes the electrical circuit when pressed alternately with opening the electrical circuit on the action of tongue 18.

The mechanism operates as follows: When wheel 50 is revolved in either direction (left or right facing front of wheel) clutch 48 causes eccentric 46 to lift dog leg shaped lever 55 (when the mechanism is in position shown in Figure 3) pin 19 resting in pin carrying area 58 is lifted; hence bail 17 is actuated or caused to pivot around shaft 16. Tongue 18 raises lever 27 which in turn lifts disk 33. Spring 42 resiliently holds pin carrying area 58 against pin 19. The surface of pin 16 extending beyond leg 14 acts as a guide against cam surface 57 pushing lever 55 outwardly against the tension of spring 42. After wheel 50 makes one complete cycle, tongue 18 comes to rest on pin 26. Should eccentric 46 be positioned as to allow lever 55 to move down a distance beyond that at which tongue 18 comes to rest on pin 26, no damage is done because pin 19 will force leg 55 outwardly against the tension of spring 42 by means of auxiliary cam area 59.

Referring particularly to Figure 8, it will be seen that no object can be crushed by this mechanism because anything caught between the movable cover 70 and the fixed sides 71, such as a cigarette 12 here illustrated, has to merely withstand the weight of disk 33, sleeve 34 and cover 70.

One of the outstanding results of the design of this unique mechanism is illustrated in Figure 7. Should cover 70, hence sleeve 34 be forced downwardly when the mechanism is in its upper operating position, pin 19 will merely ride over cam following surface 57 forcing dog leg shaped

lever 55 outwardly against the tension of spring 42. The turning of wheel 50 will cause the high point of eccentric 46 to force cam surface 57 hence leg 55 downwardly. Cam following surface 57 will ride under pin 19 until said pin falls into pin carrying area 58. Spring 42 supplies the pressure for this result to take place.

Pressure applied to cover 70 is transmitted through sleeve 34 and disk 33 to lever 27 which forces tongue 18 downwardly and through bail 17, pin 19. Cover 70 is secured to sleeve 34 by any convenient means; as by a screw 69 shown in Figure 8.

It will thus be seen that a simple inexpensive mechanism is foolproof to turning the main control wheel 50 in either direction; to prevent crushing articles or fingers between moving parts and to forcing the mechanism against itself.

What I claim is:

1. A mechanism which converts rotary motion into reciprocating motion consisting of a U-shaped frame having a U-shaped bracket secured thereto, a bail provided with a tongue pivotally mounted in said U-shaped frame, a shaft secured to said U-shaped frame and positioned adjacent said bail, a disk mounted for axial movement along said shaft, a lever pivotally mounted in said U-shaped bracket and actuated by said tongue, said lever engageable with said disk, a pin secured to said bail which engages a dog leg shaped lever actuated by an eccentric mounted on a stud secured to an arm of said U-shaped frame, a spring acting to keep said dog leg shaped lever and said pin in operating relationship, a wheel mounted on said U-shaped frame stud and held in operating relationship with said eccentric by a clutch.

2. A mechanism which converts rotary motion into reciprocating motion consisting of a U-shaped frame having a U-shaped bracket, provided with a pivotal lever, secured thereto, a bail, provided with a tongue, pivotally mounted in said U-shaped frame engaging said pivotal lever, a shaft carrying a disk with sleeve attached for axial movement thereon, secured to said U-shaped frame, said pivotal lever in sliding engagement with said disk, a pin secured to said bail, a stud secured to said U-shaped frame, an eccentric mounted on said stud, a lever engaging said eccentric and said bail pin and a spring connecting said lever, with a pin secured to an arm of said U-shaped frame.

3. A mechanism consisting of a frame, a bail provided with a tongue pivotally mounted in said frame, a pin secured to said bail, a stud mounted in said frame, an eccentric rotatably mounted on said stud, a lever engaging said eccentric and said pin secured to said bail, and a spring connected to said lever on one end and to said frame on its other end.

4. A mechanism consisting of a frame, a bail provided with a tongue pivotally mounted in said frame, a pin secured to said bail, a stud mounted in said frame, an eccentric rotatably mounted on said stud, a lever, provided with a cam surface, engaging said eccentric and said pin secured to said bail, a spring connecting said lever to said frame and an extension on said bail pivoting means engaging the cam surface on said lever.

5. A mechanism consisting of a frame, a bail provided with a tongue, pivotally mounted on a rod in said frame, a pin secured to said bail, a stud mounted in said frame, an eccentric rotatably mounted on said stud, a lever provided with a cam surface, engaging said eccentric and said

pin secured to said bail, a spring connecting said lever to said frame, an extension on said rod engaging the cam surface on said lever and a pin secured to said frame directly under said tongue.

6. A mechanism consisting of a frame, a bail provided with a tongue pivotally mounted on a rod in said frame, a pin secured to one arm of said bail, a stud secured to said frame, an eccentric rotatably mounted on said stud, a lever provided with a cam surface and pin receiving recess, engaging said eccentric and said pin secured to said bail, a spring connected to said lever and to said frame, an extension on said frame engaging said cam surface on said lever, a pin secured to said frame directly beneath said tongue, a container mounted on said frame, a shaft fixed in said frame, a sleeve mounted on said shaft for axial movement thereon, a disk fixed on either end of said sleeve, the lower disk engaging said tongue.

7. A mechanism consisting of a frame, a bail provided with a tongue, pivotally mounted on a shaft in said frame, a pin secured to one arm of said bail, a bracket provided with a pivotally mounted lever secured to the base of said frame, said tongue engaging said lever, a stud secured to said frame, an eccentric rotatably mounted on said stud, a lever provided with a cam surface and pin receiving recess engaging said eccentric and said pin secured to said bail, a spring connected to said lever and to said frame, an extension on said frame engaging said cam surface on said lever, a pin secured to said frame directly beneath said tongue, a container mounted on said frame, a shaft fixed in said frame, a

sleeve provided with a disk on its lower end mounted on said shaft, said lever engaging said disk.

8. A mechanism consisting of a frame, a bail provided with a tongue, pivotally mounted on a shaft in said frame, an orifice in said frame, a pin secured to one arm of said bail and passing through said orifice, a bracket, provided with a pivotally mounted lever, secured to the base of said frame, a stud secured to said frame, an eccentric rotatably mounted on said stud, a lever, provided with an upper and lower cam surface with a pin receiving recess in-between, engaging said eccentric and said pin secured to said bail arm, a spring connected to said lever and to said frame, an extension on said frame engaging said lower cam surface on said lever, said pin secured to said bail arm engaging said upper cam surface on said lever when the mechanism is in disorganized position, a pin secured to said frame directly beneath said tongue, a container mounted on said frame, a rod secured to the base of said frame, a sleeve provided with a disk freely movable on said rod and in said container.
9. Mechanism as defined in claim 8 further characterized in that, "a cover is secured to said sleeve."
10. Mechanism as defined in claim 8 further characterized in that, "a cover is secured to said sleeve and a housing is provided enclosing said container and mechanism."

FRED DE CESARIS.
